United States Patent Office

Des. 204,392

Patented Apr. 12, 1966

204,392

COMBINED STORAGE CABINET AND TABLE

Robert A. Clark, Allentown, Pa., assignor to Caloric Corporation, Topton, Pa., a corporation of Pennsylvania

Filed June 21, 1965, Ser. No. 85,832

Term of patent 14 years

(Cl. D33—19)

Fig. 5.

Fig. 6.

FIG. 1 is a perspective view of a combined storage cabinet and table embodying the design and shown as it appears when used primarily as a storage cabinet.

FIG. 2 is a side elevational view of the rear, or opposite side of FIG. 1.

FIG. 3 is an end elevational view showing the opposite end of FIG. 1.

FIG. 4 is a top plan view of FIG. 1.

FIG. 5 is similar to FIG. 1 but showing the top of the cabinet opened up to form a table top.

FIG. 6 is a top plan view of FIG. 5.

I claim:

The ornamental design for a combined storage cabinet and table, as shown and described.
